UNITED STATES PATENT OFFICE.

THOMAS A. SHEA, OF OSWEGO, NEW YORK, ASSIGNOR TO THE NATIONAL RAILWAY SPRING COMPANY, OF SAME PLACE.

SPRING.

SPECIFICATION forming part of Letters Patent No. 661,822, dated November 13, 1900.

Application filed August 25, 1900. Serial No. 27,993. (No model.)

To all whom it may concern:

Be it known that I, THOMAS A. SHEA, of Oswego, in the county of Oswego, in the State of New York, have invented new and useful 5 Improvements in Springs, of which the following, taken in connection with the accompanying drawings, is a full, clear, and exact description.

My invention relates to the bearing-plate 10 fitted to the end of an elliptic or semi-elliptic spring on which the load is supported; and it consists in a special construction of such bearing-plate by which it may be permanently secured to the end of the spring by mechanical 15 means without injuring or weakening the parts. Heretofore such plates have been fitted to the ends of the spring, but separable therefrom, so that they maintained their position in use, but were often lost in transpor- 20 tation and during repairs. The plates have also been permanently secured to the main leaf of the spring by welding, which is more expensive and liable to injure and weaken the parts because the heat of welding often 25 burns the main leaf or draws the temper, rendering it brittle. I have overcome these objections by making the plate with integral elongated lips of dovetail form on its under side and forming the end of the main leaf 30 with corresponding grooves or notches. The plate is then set on the leaf end, and the lips are hammered or forced inwardly to engage with the notches, whereby the plate is fixed per- 35 manently and securely in place. These lips or dovetails must be of sufficient length to give a secure hold and the notches formed exactly to correspond, so as to fill completely the notches. The notches must not be deep, for to form a deep notch in the leaf would 40 weaken it.

I have shown my invention in connection with an elliptic spring in which the bearing-plates are fitted to the lower half and the upper half and the load supported thereon.

45 My invention may be adapted to other forms of bearing-plates, such as those fitting the ends of semi-elliptic springs on which the load is supported by a hanger.

In the drawings, Figure I is a side eleva- 50 tion of an elliptic spring, showing these bearing-plates or end plates applied to the ends

of the lower half of the spring and the upper half supported thereon. Fig. II is an enlarged side elevation of a bearing-plate detached. Fig. III is an end elevation thereof. 55 Fig. IV is a top plan view. Fig. V is a vertical cross-section through the main leaf and the bearing-plate in position thereon. Fig. VI is a bottom plan of the main leaf of the spring, showing the form of the notches. Figs. VII 60 and VIII show variations in the form of these bearing-plates and hangers fitted thereto, adapted to sustain heavy loads on semi-elliptic springs, as in the case of locomotives, tenders, &c. 65

In the figures, 1 indicates the lower half of the spring, and 2 the main leaf thereof, formed with the long shallow notches 3 3 near the end, with sides inwardly inclined toward the under face to fit the dovetails 4 4 on the bearing-plate, end plate, or "dabb" 5. These bearing-plates are formed separately of malleable iron or other suitable metal, with these dovetails inclined outwardly, as best shown in Fig. III; but when the parts are assembled 70 they are forced in, filling the notches, as best shown in Fig. V, and locking the plate firmly in position. This construction of dovetails fitting the shallow rather long notches is im- 75 portant, for the plates must be locked in place 80 without any possibility of being detached in use. Here the sides 6 6 of the bearing-plate are perforated at 7 7 for the bolt 8, to which is fitted eyes on the end of the upper half 9, carrying the load. 85

In Figs. VII and VIII are shown, respec- 90 tively in side and front elevation, two forms of bearing-plate fitted to the main leaf of a semi-elliptic spring and formed to support the so-called "stirrup-hanger" 10 or the "gib- 95 hanger" 11, (indicated in dotted lines,) which carry the load. The stirrup-hanger spans the bearing-plate and depends on both sides there- 100 of. The gib-hanger depends through a hole in the bearing-plate and hangs on a cross-pin 12. These plates, made of wrought-iron or other suitable metal, are economical to make and secure in position, the spring is uninjured, it is not weakened in any way, and the hanger-plate is then fixed permanently in po- 105 sition for all purposes and cannot be removed or lost. It is particularly adapted for heavy

2
springs used for locomotives, tenders, &c., but may be applied to lighter springs and those used for other purposes.

I am aware that end plates have been suggested having lugs or projections fitting the spring-leaf to prevent lateral displacement; but those lugs did not effect permanent attachment, were not so intended, and could not be so used. Such attachment can be effected practically only by my peculiar dovetails and the peculiar notches made to receive them.

Having thus fully described my invention, what I claim, and desire to secure by Letters Patent, is—

1. In combination in a semi-elliptic spring, having notches in its main leaf near the ends, and a bearing-plate with dovetails corresponding to said notches and adapted to be forced inwardly to fill the notches engaging with the main leaf and securing the plate permanently in position.

2. In combination with a spring having elongated notches on each side near its ends,

hanger-plates fitting the ends of the spring 25 and having elongated integral dovetails on their upper side, said dovetails inclining slightly outwardly and being beveled on their inner surfaces and adapted to be forced inwardly to fill the notches and secure the plate 30 permanently in position.

3. In combination a spring-leaf formed with elongated shallow notches on both sides of each end, said notches being slightly deeper on the under side of the spring and a hanger-plate provided with elongated dovetails corresponding to said notches, said dovetails inclining slightly outwardly and being adapted to be forced in to fill the notches and secure the plate permanently in position on the 40 spring.

In testimony whereof I have hereunto signed my name.

THOMAS A. SHEA. [L. S.]
